United States Patent Office

Des. 197,280
Patented Jan. 7, 1964

197,280

EXECUTIVE TYPE TELEPHONE STAND

Henry Dreyfuss, South Pasadena, Calif., assignor to Bell Telephone Laboratories, Incorporated, New York, N.Y., a corporation of New York

Filed Nov. 5, 1962, Ser. No. 72,370

Term of patent 14 years

(Cl. D26—14)

FIG. 1

FIG. 2

FIG. 3

FIG. 1 is a front perspective view of an executive type telephone stand, showing my new design;

FIG. 2 is a top plan view of the executive type telephone stand shown in FIG. 1; and

FIG. 3 is a side elevational view thereof.

The dominant features of my design reside in the portion shown in solid lines in the drawing.

I claim:

The ornamental design for an executive type telephone stand, as shown and described.
